INVENTOR,

James W. Bonta

By S. J. Van Stavoren
ATTORNEY

UNITED STATES PATENT OFFICE.

JAMES W. BONTA, OF PHILADELPHIA, PENNSYLVANIA.

TELEPHONE-TRANSMITTER.

SPECIFICATION forming part of Letters Patent No. 352,177, dated November 9, 1886.

Application filed March 11, 1886. Serial No. 194,802. (No model.)

To all whom it may concern:

Be it known that I, JAMES W. BONTA, a citizen of the United States, residing at Philadelphia, in the county of Philadelphia and State of Pennsylvania, have invented certain new and useful Improvements in Telephonic Transmitters, of which the following is a specification, reference being had therein to the accompanying drawings, wherein—

10 to Figure 1 is a sectional elevation of a telephonic transmitter embodying my improvements. Fig. 2 is a central horizontal section of transmitter-box and plan of diaphragm, electrodes, table, and its support attached to the hinged front of the box; and Fig. 3 is a detail elevation of loose or ball electrode, grooved table, wedge, and support for the latter.

15 My invention has relation to that form of telephonic transmitter wherein an electrode is affixed to the diaphragm, and a loose or movable electrode, preferably a ball, is supported upon an inclined table adapted to be raised or lowered by means of a wedge to alter or adjust the initial contact-pressure between the electrodes; and it has for its object simplicity of construction and arrangement of parts, whereby easy access to the electrodes and table may be obtained for adjusting the height 30 of the table or platform to vary the initial contact-pressure between the electrodes.

25 My invention accordingly consists of the combination, construction, and arrangement of parts, as hereinafter described and claimed.

35 A represents a box or casing, having a hinged front or door, a, provided with a mouth-piece, a', and to which is secured in any suitable manner the diaphragm B, having affixed thereto a carbon electrode, b. To the door is also 40 secured a horizontally-arranged platform, C, which projects into the box A and rests upon a fixed block or check-piece, a''. Upon platform C rests a wedge, D, having a movement to and from the diaphragm, and forms support for preferably a carbon-plate, F, having 45 preferably a longitudinal groove, f, in its upper side for the reception of a carbon ball or loose electrode, G, which contacts with the diaphragm-electrode, as shown. By pushing

or moving the wedge D to and from the diaphragm B, the table F is elevated or depressed more or less to correspondingly move the electrode or ball G and place more or less of its mass or weight either above or below the axial line of the diaphragm-electrode b, to obtain 50 a variation in the initial contact-pressure between the electrodes.

55 As the platform C is secured to the door or front a, the wedge D, plate F, and ball G are carried thereby and maintained in their relative positions when the door is opened or closed.

Any suitable inductorium, K, may be employed, the primary 1 of which includes the diaphragm-electrode b, ball G, table F, and 60 battery 3, and the secondary 2 forms part of the line.

I do not claim, broadly, in this application the means for vertically adjusting the platform without tilting the same, as that forms 70 the subject-matter of an application filed on even date with this and numbered 194,801.

What I claim is—

1. The combination of a box, A, having hinged door a, a diaphragm having a fixed electrode and a platform secured to the door, a wedge resting upon the platform, a plate supported by the wedge, and loose ball or electrode upon said plate in contact with the diaphragm-electrode, substantially as shown and described. 75

2. The combination of case A, having check-piece a'', hinged door a, diaphragm B, having electrode b, and platform C, secured to the door, wedge D, grooved plate F, and loose ball or electrode G, substantially as shown 80 and described.

3. The combination of case A, having removable front a, diaphragm B, platform C, secured to the door, wedge D, carbon-plate F, and loose ball or electrode G, substantially as 85 shown and described.

In testimony whereof I affix my signature in presence of two witnesses.

JAMES W. BONTA.
